R. R. CANDEE

BAILER BOTTOM

Filed Aug. 7, 1922

Inventor:
Raphael R. CANDEE
by Hazard & Miller
Attorneys.

UNITED STATES PATENT OFFICE.

RAPHAEL R. CANDEE, OF McKITTRICK, CALIFORNIA.

BAILER BOTTOM.

Application filed August 7, 1922. Serial No. 580,369.

To all whom it may concern:

Be it known that I, RAPHAEL R. CANDEE, a citizen of the United States, residing at McKittrick, in the county of Kern and State of California, have invented new and useful Improvements in Bailer Bottoms, of which the following is a specification.

This invention relates to well sinking tools and more particularly to bailers.

10 The bailer forming the subject matter of the invention includes an upper receptacle or shell to the lower end of which is connected a swivel shoe or bottom section and in between these sections there is arranged a self-closing valve of suitable type. The bailer body includes a portion telescopically fitting in the shoe and which closely approaches a valve seat or annulus.

It is an object of the present invention to 20 provide for a suitable degree of rotation of the inner telescopic member so as to permit the registration of outlet ports provided in the swivel shoe and in the telescopic end of the body so as to effect the discharge of 25 the contents from the bailer and to provide such a construction that will insure the accurate readjustment of the parts, without jamming, when the ports are turned relatively out of register. In other words, 30 it is an object to provide relatively rotative means which can be adjusted according to the use of the device and be kept free from jamming or clogging by the entrance of the material from the chamber of the bailer.

35 Other objects and advantages will be made manifest in the following specification of an embodiment of the invention illustrated in the accompanying drawings, wherein:

40 Figure 1 is a side elevation of the bailer with the bottom in closing position.

Figure 2 is a central longitudinal section of the bailer with the bottom in open position.

45 Figure 3 is a transverse section on line 3-3 of Figure 1 showing the bottom in closed position.

Figure 4 is a transverse section on line 4-4 of Figure 2 showing the bottom in open position.

50 Figure 5 is a detail of the interlocking means.

The bailer consists of an upper body 2 of any suitable dimensions and shape, 55 though preferably being cylindrical, and

having any suitable bailing loop 3. To the lower end of the bailer body 2 there is suitably connected a section consisting of a bushing 4 which, in the present case, is shown as pinned or riveted at 5.

To the lower end of the bushing 4 there is rotatively attached a cylindrical bottom or shoe section 6 which is peripherally internally threaded at 7 onto the lower end of the bushing and may be turned up toward 65 or against an annular shoulder 8 thereon. The lower portion of the bottom 6 is open and has peripheral openings 9. Extending around the bore of the shoe is an inwardly extending shoulder 10 within which is a 70 mouth 11 and upon the top of the shoulder 10 there rests a removable annulus or valve seat 10^a which has on its upper portion a flat shoulder 10^b which is engaged by the contiguous end 4^a of the bushing 4 when the 75 shoe 6 is screwed up tight. The valve seat 10^a has a cylindrical shoulder 10^c which is encompassed by the bushing end 4^a so that this will slide up and down toward the shoulder 10^b when the shoe is rotated on the 80 bushing 4 so as to bring the port 14 in the bushing into register with the port 13 in the side of the shoe for the discharge of material from the bailer.

The snug telescopic fit of the bushing end 85 4^a around the rim 10^c of the valve seat prevents the material in the bailer from passing in below the transverse end edge of the bushing end 4^a.

There is provided a valve 12 which is 90 hinged at 12^a on top of the valve seat 10^a.

If desired an interlock may be formed between the bushing end 4^a and the valve seat or annulus 10^a and this may be secured as by means of a lug 10^e provided on one 95 side of the valve seat to project into a recess or notch 4^b in the end edge of the bushing part 4^a.

From the above it will be seen that the shoe 6 can be unscrewed or backed off sufficiently by a quarter rotation to register the discharge ports 13 and 14 without the end edge of the bushing part 4^a uncovering the wall or rim 10^c of the valve seat.

Further embodiments, modifications and 100 variations may be resorted to within the spirit of the invention as claimed.

What is claimed is:

1. A deep well bailer comprising a bailer body having a ported lower end portion, a 110

- ported swiveled bottom section connected to said lower end portion, and a valve seat having a peripheral rim about which the lower end of the bailer body telescopes and 5 is adapted for some longitudinal movement before uncovering the said rim as the bottom section is turned to register the ports.
2. A bailer comprising a ported body portion and a ported shoe rotatively mounted 10 upon said body portion, and a member interposed between said shoe and the end of said body portion which telescopes in the shoe, said member having a peripheral rim rotatively fitting the telescopic end of said 15 body and upon which the said end has a longitudinal movement when the body and shoe are rotated to register discharge ports.
3. A bailer comprising a ported shoe section, a valve seat mounted in said section 20 and forming therewith an annular pocket having a cylindrical wall, and a ported body section telescopic in the shoe section and having its end sliding in the said pocket so that the shoe and the said body sections may 25 be longitudinally shifted without withdrawing the end of the body section from said pocket when the shoe and the body section are partially rotated to register coordinate discharge ports.
4. In a deep well bailer, a ported shoe section, a valve seat arranged in said section, and a ported closure sleeve rotative and 30 slideable in said shoe and adapted to clamp the seat in place.
5. In a deep well bailer, a ported shoe section, a valve seat arranged in said section, and a ported closure sleeve rotative and slideable in said shoe and adapted to clamp the seat in place, the said seat having a recessed 35 rim over which the sleeve slides.
6. A deep well bailer, comprising a bailer body, and a turnable bottom section connected to the body, and having a valve, a means above the valve for providing for removal of the contents from the bailer upon 40
- relative rotation of the body and bottom to unloading position.
7. A bailer comprising a body, a bottom rotatably attached to the lower end of the bailer body and having an inlet valve, the 50 bailer body and the bottom having outlet ports adapted to be registered to permit the withdrawal of the contents from the bailer.
8. A bailer consisting of a cylindrical upper body section, and bushing attached to the lower end of such body section and having an outlet port in its lower end, and a bottom part turnably mounted upon the bushing and having an outlet port to be registered with the port in the bushing to permit the withdrawal of the contents of the bailer. 55
9. A bailer consisting of a cylindrical upper body section, and a bushing attached to the lower end of such body section and having an outlet port in its lower end, and a bottom part turnably mounted upon the bushing and having an outlet port to be registered with the port in the bushing to permit the withdrawal of the contents of the bailer, said bottom having an inlet valve. 60
10. A deep well bailer, comprising a bailer body, a bottom section threaded on the lower end of said body and having a valve, said body and bottom having ports above the valve for providing for the removal of the 75 contents from the bailer.
11. A deep well bailer comprising a bailer body having a threaded end and a shoulder at said threads, said body having an outlet port, a bottom section turnably mounted on 80 said threads and having an outlet port, whereby when the bottom is turned in one direction the ports are registered and when turned in the other direction the bottom is jammed against said shoulder and the ports 85 held out of register.

In testimony whereof I have signed my name to this specification.

RAPHAEL R. CANDEE.
